DUST GUARD

Ernest Armstrong, Camden, N. J.

Application March 18, 1932, Serial No. 599,666

9 Claims. (Cl. 286—6)

This invention relates to dust guards used in connection with car axles, and within railway journal boxes.

Dust guards, as commonly used, are positioned within a narrow pocket, next to an outer wall of the journal box, and undergo considerable movement during the running of the train. During such movement they have to withstand strains that tend to distort them during their frictional action in contact with the walls of the pocket, accompanying the transverse action of the axle, relative to the box.

It is therefore one of the objects of my invention to provide a construction of dust guard which shall withstand distorting strains, by being flexible and elastic for slight bending, particularly with respect to the plane of the dust guard, to be durable under such use, so that it will yield rather than crack or break under the distorting strains, and will quickly resume its normal flat shape, for freedom of movement, within the pocket it occupies, after the occasion for the distorting strains has disappeared.

Another object of my invention is to provide as cheap and durable a form of dust guard as possible, which will also fulfill the above named object. Such a dust guard, I prefer to make up of pieces of thin boards of wood or other fibrous material, of proper thickness, using scrap wood where it is available, to save on the cost of the material, using such material exclusively for the dust guard, with the exception of the necessary fasteners, to hold the parts together, thus reducing the dust guard to as simple a form as possible, consistent with its practical and durable adaptability for its particular use.

A further object is the selection of such inexpensive joining pieces as will afford flexibility in all directions, where the parts on the dust guard are joined together. For this purpose I prefer to use the common sheet metal corrugated fasteners, and arrange the pieces, if wood is used, in position to have the grain of the wood run tangential to the curvature of the axle or shaft it comes in contact with, having each piece of wood thus arranged in its contact with the axle or shaft, rather than have the grain of the wood abut the axle or shaft surface, so as to avoid splitting the wood, and in addition, to further strengthen the dust guard pieces as a unit, I prefer to bind the parts together at their periphery by a wire drawn tight around the dust guard, preferably in a groove provided for it, having the twisted ends of this

binding wire pushed back into a pocket in the wood, to be out of contact with the walls of the dust guard pocket, in the journal or bearing box.

With these and other objects which will hereinafter appear, my invention resides in certain construction adapted to fulfill the above named objects. One embodiment of my invention is illustrated in the drawing, its construction is explained and what I claim is set forth.

In the drawing,

Figure 1 is a flat side elevation of a dust guard embodying my invention.

Figure 2 is an edge elevation of the dust guard shown in Figure 1, taken in the direction of the arrow 2, of Figure 1.

In the figures, the body of the dust guard is shown to be made up of the square-ended piece of thin boards of wood, marked 10, opposite which is the piece of wood marked 11, having the grain of both pieces of wood, 10 and 11, run approximately parallel. Between the pieces 10 and 11, and abutting the same, are the pieces of wood 12 and 13, the grain of each of these pieces running transverse to that of the pieces 10 and 11. The inner edge of each of these pieces 10, 11, 12 and 13, is curved in its plane to form, as assembled, the circle of the opening 14, which is made in size to fit that part of the axle or shaft of the car wheel, upon which it rides, when positioned therewith, surrounding the axle or shaft and within the journal box. The outer contour of the body of the dust guard is formed and proportioned to fit within the narrow pocket of the particular type of journal or bearing box for which it is intended to fit.

At each of the places where the pieces 10, 11, 12 and 13 abut one another, there is provided a corrugated sheet metal fastener 15, embedded in the abutting pieces, to be within the surfaces thereof and be across the joint thereof, fixing them together. The part of the corrugated fastener 15, which crosses the abutting faces, of adjoining pieces, being of sheet metal, affords, in the longitudinal direction of the fastener, a flexibility that permits the adjoining pieces to have a slight movement longitudinal of their abutting edge faces, as these pieces remain in the same plane with one another. The corrugations, in themselves, afford an angular movement of the fastener itself, within its own plane, thus permitting a slight angular movement about an axis which is the line of contact, of the faces, of the abutting pieces. There is

also permitted an angular movement of the pieces relative to one another, at the abutting edge faces thereof, in another place which passes through the line of abutment transverse to the place of the dust guard. But this latter movement would not be possible if more than one fastener were used to connect a single joint of abutting point edge faces. Considering the variety of angular movements possible with the 10 corrugated fasteners used in joining the parts together it is evident that such fasteners are particularly suitable for the purpose used.

For additional security, I prefer to use a strong wire binder 16, positioned within a peripheral groove 17, to bind the parts together, at their periphery. Where this wire 16 crosses the joints, and is within a groove, it affords a slight movement of the adjoining pieces, in the direction of the length of the abutting edge faces, 20 and also an angular movement of the adjoining pieces, as hinging upon the line of contact of the abutting edge faces thereof. On account of the penetrable flexibility of the wood used, any slight angular movement tending to move 25 the adjoining pieces in opposite directions, where the wire crosses the joint between them, will be permitted. Therefore, even with the wire binder, 16, the complete unitary structure of such a dust guard, has an angular flexibility 30 from the plane thereof, in all directions afforded by its particular jointed structure.

The ends 18, of the wire 16, are twisted together after the wire 16 has been drawn tightly, to bind about the body of the dust guard. The 35 twisted ends 18, of the wire are embedded in a pocket 19, in the line of the groove 17, to be wholly within the edges of the periphery of the dust guard, so that there will be no projecting wire parts to contact a wall of the dust 40 guard pocket, within the journal box.

If the dust guard body is made up of a single sheet or board of wood or other fibrous material, with a binding wire 16, at its periphery, it will be strengthened against splitting. The 45 same is true where a laminated material of wood or other fibrous material is used, having a binding wire tightly drawn about its periphery.

While I have shown and described in detail 50 parts which make up one embodiment of my invention, including the shape shown, changes therein, including a different shape, can be had, without departing from the spirit and scope of my invention. I therefore wish to include all 55 forms and changes which come within the purview of the following claims.

The invention is hereby claimed as follows:

1. A dust guard unit adapted for use in connection with a shaft entering a bearing box, to 60 encircle the shaft therein, said dust guard unit being composed of material which has a longitudinally extending grain, said dust guard unit being constructed in sections, to have the grain of sections, disposed on opposite sides of the 65 encircled shaft, run approximately parallel, and to have the remaining sections of said dust guard unit extend from one to the other of said first mentioned sections, between the ends thereof and having the grain of the said remaining 70 sections run transverse in direction to the grain of the first mentioned sections, all of said sections presenting an opening cut through the grain thereof and corresponding in size to the diameter of the shaft.

2. A dust guard for an axle within a bear-

ing box, said dust guard comprising a plurality of flat, wooden sections, the grain of the wood of two oppositely disposed sections running approximately parallel, and intermediate sections having the grain run transverse in direction to the grain of the first mentioned sections, yielding joints connecting the abutting edges of contiguous sections, the innermost edges of said sections being arched to come in contact with the circumferential surface of said axle. 80

3. A dust guard constructed in accordance with claim 2, and a binder about the periphery of the unit thus formed, adapted to hold all parts intact. 85

4. A dust guard constructed in accordance with claim 2, with a peripheral groove about said guard and a binder for the said sections, positioned within said groove, adapted to hold the parts intact. 90

5. A dust guard comprising a flat body, with a hole therethrough and adapted to fit a shaft entering a bearing box, said guard being constructed of a plurality of flat pieces placed in edge abutment, having all said pieces in one plane, the abutting edge faces of said pieces extending continuously from the flat face on one side to the flat face on the opposite side of each flat piece, elastic and flexible means extending across the abutting faces of adjoining flat pieces, said dust guard of said flat pieces, positioned 100 in abutment all in the same plane, presenting a substantially flat face on one side, made up of the flat faces of said flat pieces on that side, and the flat faces on the opposite side of said flat pieces forming together the opposite side 110 of said dust guard.

6. A dust guard adapted for use around a shaft in a bearing box, said dust guard comprising a flat body with a central opening therethrough, adapted to fit said shaft, said body 115 being formed of a plurality of longitudinally fibrous and jointed members, positioned about said opening, in abutment with one another, at their edges to have the fibers of said members individually tangential in direction, with respect to said central opening and joining devices connecting contiguous members in edge abutment, and affording by their structure, an angular flexibility to said flat body, with respect to the plane thereof. 120

7. A dust guard made in accordance with claim 5, and a binder about the peripheral edge of said dust guard. 125

8. A dust guard made in accordance with claim 5, wherein the flexible means connecting said abutting pieces, consists of corrugated sheet metal fasteners, embedded in the adjoining, and edge abutting, flat pieces, and positioned across the abutting edges of said pieces. 130

9. A dust guard adapted for use around an axle in a journal box, said dust guard comprising a flat body with a central opening adapted to fit said axle, a plurality of longitudinally fibrous and joined members forming said body, and positioned about said opening, in abutment to one another, to have the direction of fibre of each member transverse to that of its adjoining members and means positioned at the joint faces of adjoining members, connecting the same together, at one portion in the 145 length of said faces, whereby a relative angular movement between adjoining members is afforded.

ERNEST ARMSTRONG.
